HAIR DRYER

Peter W. Cherry, Monroe, and Alfred W. Wakeman,
Newton, Conn.; said Wakeman assignor to said Cherry

Application June 2, 1958, Serial No. 51,157

Term of patent 14 years

(Cl. D86—10)

Fig. 1 is a side elevational view of a hair dryer showing our new design; both sides being identical in appearance;

Fig. 2 is a bottom plan view; and

Fig. 3 is a top plan view thereof.

We claim:

The ornamental design for a hair dryer, substantially as shown and described.
